UNITED STATES PATENT OFFICE.

WILLIAM T. HORMES, OF GOVANS, MARYLAND, ASSIGNEE TO SOLOMON HIMMEL, OF BALTIMORE, MARYLAND.

DISPLAY-RACK.

1,213,646.

Specification of Letters Patent. Patented Jan. 23, 1917.

Application filed January 20, 1915. Serial No. 3,332.

To all whom it may concern:

Be it known that I, WILLIAM T. HORMES, a citizen of the United States, residing at Govans, in the county of Baltimore and State of Maryland, have invented new and useful Improvements in Display-Racks, of which the following is a specification.

This invention is a device for displaying or exhibiting goods, and relates to that type 10 of display device wherein a rotatable rack is employed for supporting the goods to be displayed, which rack is movable to and from a position within a case or compartment. Such cases or compartments are usually 15 constructed with glass walls or panels, so that the goods on display may be readily seen by prospective customers passing the same, and at the same time be protected from dust and promiscuous handling. 20 When it is desired to more closely inspect the goods upon display, the rack is moved to the forward edge of the case or compartment, and then rotated at will, to permit of convenient inspection and selection. In 25 view of the fact that economy of floor space demands that the area occupied by the case or compartment be as small as possible, it is usually customary to construct the case or compartment of oblong shape, the rack 30 or supporting member conforming to this shape, being of a length greater than the width of the case. To provide the necessary clearance for the rotation of a rack, said rack is so mounted as to be bodily 35 moved to a point near the front of the case, the distance being sufficient to permit the ends of the rack to clear the rear wall or panel of the case, when the rack is rotated. Heretofore display racks of this type have 40 been usually employed for the storing and display of ready made garments, such as men's and boys' clothing, women's dresses and the like.

One of the objects of the present invention 45 is to broaden the field of usefulness of such display racks, by providing simple and efficient means whereby smaller articles of merchandise may be stored and exhibited, and yet be easy of access when removal or 50 close examination is desired.

A further object is to provide means for supporting and displaying articles that are not as conveniently supported as garments,

by providing a plurality of independent panels or supports, each capable of supporting articles to be displayed, and all combined in a unitary structure mounted upon a rotatable support arranged to be moved back and forth within the case or compartment, said panels or supports being free to 60 swing when the rotatable support is in its outermost position.

A further object is to provide means for preventing independent swinging of the panels or supports except when the rotatable support is in its outermost position.

A further object is to provide means for automatically releasing said panels when the rack has been moved to its forward or outermost position, and rotated to the proper 70 position for displaying the merchandise supported by the panels.

A further object is to provide means to automatically close and lock said panels as the rotatable support is turned into position for returning the device into the case, thereby preventing the panels fouling any portion of the walls of the case.

The invention will be hereinafter fully set forth and particularly pointed out in the 80 claims.

In the accompanying drawings: Figure 1 is a top plan view illustrating a case containing my improved display rack, the top of the case being removed, the rack being 85 shown in its rearmost position. Fig. 2 is a similar view illustrating the rack in its outer position. Fig. 3 is a front elevation with the rack in its rearmost position within the case. Fig. 4 is a detail view illustrating one of the panels. Fig. 5 is a detail view illustrating the automatic locking device for the panels. Fig. 6 is a detail of the panel controlling cam. Fig. 7 is a similar view of a slight modification of the cam. 90 Fig. 8 is a detail view illustrating the panel spacing members. Fig. 9 is a detail view of the means for locking the rack against rotation when in rearward position.

Referring to the drawing, 10 designates 100 a case of any suitable or preferred construction, that shown being provided with front or door sections 11 constructed of glass, and capable of being removed to permit movement of the display rack to a forward position. The bottom of the case is provided

with a channel 13, the upper edges of which are formed as guides 14, between which the support or carriage 15 is mounted to reciprocate. Said carriage is provided with a tubular boss 16 which rotatably supports a shaft 17 provided with upper and lower cross heads 18 connected by vertical rods 19.

The wings or panels for supporting the goods to be displayed, are each built up of a metal frame-work, 20, preferably tubing, 16 properly braced, containing a suitable panel 21, which may or may not be covered with a soft material, such as burlap. The frame of each wing is provided at top and bottom 15 on one side, with pintles 22, 23, the pintles 22 being somewhat longer than the pintles 23. These pintles are designed to enter suitably spaced holes or perforations in the cross-heads 18, the pintles 22 being of sufficient height to permit of their insertion into 20 the holes of the upper cross-head and to allow the lower pintles 23 to be swung in over the lower cross-head and dropped into the proper hole in the latter. In this manner 25 the wing is securely retained in position but free to swing from side to side on the pintles. To one end of each panel is secured a spacing member 25 provided with fingers 26 extending between contiguous 30 panels for the purpose of preventing collision between the panels and interference of the goods carried by the respective panels.

The means for controlling the panels during the reciprocal movements of the carriage, comprises a disk 27 preferably circular in form with its center conforming to the axis of the shaft 17, said disk being rigidly secured to the carriage in any suitable manner. The edge of said disk, at the forward portion thereof is provided with 40 a cam slot 28, preferably of approximately V-shape, the walls of the slot being rounded and flared, as clearly illustrated in Fig. 6. Rigidly secured to the cross heads 18 are 45 guide rods 29 which are suitably connected by brace rods 30. The panels, as shown, are arranged in two parallel series, the end panels 31 of each series being connected by links 32 to flanges 33 of slides 34, 50 mounted to reciprocate upon the guide rods 29. Each slide 34 is provided at its forward edge with a lug or projection 35, and 55 cross heads 18 act to hold said lugs or projections in yielding engagement with the peripheral edge of the disk 27.

If desired, means may be provided for locking the shaft 17 against rotation during the reciprocal movement of the carriage, 60 and for purposes of illustration I have shown the construction described and claimed in Letters Patent 991,164, granted to Andrew E. Miller, May 2, 1911. This construction comprises a disk 40 secured to the shaft 17 and provided with pins 41 extended be-

tween the arms 42 of a guide provided with an enlarged portion 43. The arms 42 engaging with the pins 41 prevent rotation of the shaft 17 until the pins are moved into the enlargement 43.

In practice the panels are arranged in oppositely disposed sets each comprising a plurality of panels, the combined length of the sets being greater than the width of the cabinet.

The operation is as follows:—When the parts are in the position illustrated in Fig. 1, the spring 36, acting on the slides 34, holds the lugs or projections 35 against the edge of the disk 27, and owing to the fact that said slides cannot move inwardly toward the shaft 17, the end panels 31 are held against pivotal movement by reason of the connection of the links 32 with said end panels and said slide. When it is desired to display the goods supported by the panels, the carriage supporting the shaft 17 is moved forward to the position illustrated in Fig. 2, and the shaft rotated so as to bring the cross heads 18 substantially parallel with the rear wall of the case. As the shaft is rotated the lug or projection 35 of one of the slides 34 engages one of the rounded walls of the slot 28, and as the rotation of the shaft continues, the spring 36 draws said lug or projection into said slot. This movement causes the slide 34 to also move toward the shaft 17, and through the medium of the links 32, moves the end panels to which said links are connected, 100 outwardly against the ends of the front opening of the case, as illustrated in Fig. 2. In this position the end panels engaging the ends of the front opening will prevent rotation of the shaft. At the same time 105 the remaining panels, between the end panels exposed before the front opening of the case, may be swung on their respective pivots to permit of ready and easy examination of the articles supported by the panels. 110 When it is desired to return the rack to its rearward position, or to bring the rear panels to the front, the rack is rotated by the operator, causing the slide 34 to move out of the slot 28, thereby closing the end 115 panels into parallel position with the remaining panels of the series, and as the rotation of the rack is continued, the said panels will be locked when the lug 35 engages the circular periphery of the cam. 120 The rack may then be rotated until it is in position to be returned within the case, or if it is desired to inspect the remaining panels, the rotation is continued until the finger 35 of the other slide 34 is moved into 125 the slot 28 by the spring 36.

In Fig. 7 is illustrated a modified form of the cam. In this type the cam is in the form of a circular flange 27' provided with an offset portion 28' similar in contour to the 130

slot 28. The slides 34' are mounted upon guide rods 29' and are connected by links 32' with the end panels 31'. Springs similar to spring 36, Figs. 1 and 2, act to hold 5 the slides in engagement with the inner face of the flange 27'. The operation is the same as that of the first described form.

The advantages and operation of my improved display rack will be readily apparent 10 from the foregoing description. By providing a series of pivoted panels mounted upon the rotatable and reciprocable support located within a suitable casing I have provided simple means by which small articles 15 may be conveniently supported and displayed. My improved display rack is particularly useful for supporting and displaying small articles, such as lace collars, cuffs, ties, vests, and similar articles, although not 20 limited thereto, as means may be provided for supporting lace curtains, shoes, hosiery, and almost any article which it may be desirable to display in this manner.

It will be understood that while the invention 25 is illustrated and described as applied to a structure including a case or cabinet, it is not limited thereto, as a display rack of considerable utility may be constructed in accordance with the invention, with which a 30 case or cabinet is not required.

Having thus explained the nature of my invention and described an operative manner of constructing and using the same, although without attempting to set forth all 35 of the forms in which it may be made, or all of the forms of its use, what I claim is:—

1. In a display rack of the character described, the combination with a case or cabinet, of a rotatable shaft mounted to reciprocate to and from a position within the case or cabinet, and a plurality of oppositely disposed sets of parallel panels supported by 40 said shaft for pivotal movement independent of the rotation of said shaft, the combined length of the sets of panels being greater than the width of said case or cabinet.

2. In a display rack of the character described, the combination with a case or cabinet, of a rotatable shaft mounted to reciprocate to and from a position within the case or cabinet, a plurality of parallel panels arranged in oppositely disposed sets and pivotally supported by said shaft, and means 55 independent of the case or cabinet for simultaneously preventing pivotal movement of all said panels.

3. In a display rack of the character described, the combination with a case or cabinet, of a rotatable shaft mounted to reciprocate to and from a position within the case or cabinet, a plurality of parallel panels arranged in oppositely disposed sets and pivotally supported by said shaft, and means 60 independent of the case or cabinet co-operat-

ing with the end panels for simultaneously preventing pivotal movement of all of said panels.

4. In a display rack of the character described, the combination with a case or cabinet, of a rotatable shaft mounted to reciprocate to and from a position within the case or cabinet, spaced apart cross heads secured to said shaft, and a plurality of parallel panels arranged in oppositely disposed sets and 70 pivotally attached to opposite edges of said cross heads, the combined length of the sets of panels being greater than the width of said case or cabinet.

5. In a display rack of the character described, the combination with a case or cabinet, of a rotatable shaft mounted to reciprocate to and from a position within the case or cabinet, spaced apart cross heads secured to said shaft, a plurality of parallel 80 panels arranged in oppositely disposed sets and pivotally supported by said cross heads, and means independent of the case or cabinet co-operating with the end panels for simultaneously preventing pivotal movement 90 of all of said panels.

6. In a display rack of the character described, the combination with a case or cabinet, of a rotatable shaft mounted to reciprocate to and from a position within the case 95 or cabinet, a plurality of parallel panels arranged in oppositely disposed sets and pivotally supported by said shaft, and means independent of the case or cabinet for simultaneously preventing pivotal movement 100 of all of said panels, and for automatically releasing all of the panels of either set when the shaft is in predetermined positions in its rotative movement.

7. In a display rack of the character described, the combination with a case or cabinet having a front opening, of a rotatable shaft mounted to reciprocate to and from a position within the case or cabinet, a plurality of panels arranged in parallel relation and pivotally supported by said shaft, and means for locking the end panels in engagement with the ends of said front opening to prevent pivotal movement of said shaft.

8. In a display rack of the character described, the combination with a case or cabinet, of a rotatable shaft mounted to reciprocate to and from a position within the case or cabinet, a plurality of panels arranged 110 in parallel relation and pivotally supported by said shaft, a non-rotatable cam disk concentric with said shaft, and means co-operating with said disk for normally preventing pivotal movement of said panels on their 115 support.

9. In a display rack of the character described, the combination with a case or cabinet, of a rotatable shaft mounted to reciprocate to and from a position within the 120

case or cabinet, a plurality of panels pivotally supported by said shaft, a non-rotatable cam disk concentric with and independent of the shaft, slides in engagement with said cam disk, and means connected with said slides for preventing pivotal movement of said panels on their support.

10. In a display rack of the character described, the combination with a case or cabinet, of a rotatable shaft mounted to reciprocate to and from a position within the case or cabinet, a plurality of panels pivotally supported by said shaft, a non-rotatable cam disk concentric with and independent of said shaft, slides in engagement with said cam disk, and links connecting the end panels with said slides.

11. In a display rack of the character described, a shaft, a plurality of panels arranged in parallel relation and pivotally supported by said shaft, a cam disk concentric with said shaft, said cam disk and said shaft being relatively rotatable, and means coöperating with said cam disk for normally preventing pivotal movement of said panels on their support.

12. In a display rack of the character described, the combination with a case or cabinet, of a rotatable shaft mounted to reciprocate to and from a position within the case or cabinet, a plurality of panels pivotally supported by said shaft, guides supported by said shaft, slides mounted to reciprocate on said guides, links connecting the end panels with said slides, and means for preventing movement of said slides upon said guides.

13. In a display rack of the character described, the combination with a case or cabinet, of a rotatable shaft mounted to reciprocate to and from a position within the case or cabinet, a plurality of panels pivotally supported by said shaft, movable means carried by said shaft for imparting pivotal movement to the end panels, and means co-operating with said movable means and stationary with respect thereto for controlling the actuation thereof.

14. In a display rack of the character described, the combination with a case or cabinet, of a rotatable shaft mounted to reciprocate to and from a position within the case or cabinet, a plurality of panels pivotally supported by said shaft, movable means carried by said shaft for imparting pivotal movement to the end panels, and a cam concentric with said shaft and stationary with respect thereto for controlling the actuation of said panel moving means.

15. In a display rack of the character described, the combination with a case or cabinet, of a rotatable shaft mounted to reciprocate to and from a position within the case or cabinet, a plurality of panels pivotally

supported by said shaft, guides supported by said shaft, slides mounted to reciprocate on said guides, links connecting the end panels with said slides, and a non-rotatable cam concentric with and independent of said shaft and engaged by said slides.

16. In a display rack of the character described, the combination with a case or cabinet, of a rotatable shaft mounted to reciprocate to and from a position within the case or cabinet, a plurality of panels pivotally supported by said shaft, slides connected with the end panels, a non-rotatable cam concentric with and independent of said shaft, and means for yieldingly holding said slides in engagement with said cam.

17. In a display rack of the character described, the combination with a case or cabinet, of a rotatable shaft mounted to reciprocate to and from a position within the case or cabinet, a plurality of panels pivotally supported by said shaft, a non-rotatable cam concentric with and independent of said shaft, slides connected with the end panels, and springs for holding the slides yieldingly against said cam, said springs being connected to a part carried by said shaft.

18. In a display rack of the character described, the combination with a case or cabinet, of a rotatable shaft, mounted to reciprocate to and from a position within the case or cabinet, a plurality of panels pivotally supported by said shaft, a non-rotatable cam concentric with said shaft and provided with a slot leading in from the periphery thereof, slides connected with the end panels and adapted to enter said slot, and springs connected with said slides and holding the latter yieldingly against said cam.

19. In a display rack of the character described, the combination with a case or cabinet, of a rotatable shaft mounted to reciprocate to and from a position within the case or cabinet, a plurality of panels pivotally supported by said shaft, a non-rotatable cam concentric with said shaft and provided with a slot leading in from the periphery thereof, and means yieldingly engaging said cam and adapted to enter said slot to impart pivotal movement to the end panels.

20. In a display rack of the character described, the combination with a case or cabinet, of a rotatable shaft mounted to reciprocate to and from a position within the case or cabinet, a plurality of panels pivotally supported by said shaft, a non-rotatable circular cam concentric with said shaft and provided with a slot leading in from the periphery thereof, guide rods carried by said shaft, slides mounted to reciprocate upon said guide rods and adapted to enter said slot, links connecting said guide rods with the end panels, and means for holding

said slides yieldingly against the periphery of said cam.

21. In a display rack of the character described, the combination with a case or cabinet, of a rotatable shaft mounted to reciprocate to and from a position within the case or cabinet, and a plurality of panels arranged in parallel relation and pivotally supported by said shaft, means for locking 10 said panels against pivotal movement and including means operated by rotation of said shaft to initiate pivotal movement of the end panels.

22. In a display rack of the character described, the combination with a case or cabinet, of a rotatable shaft mounted to reciprocate to and from a position within said case or cabinet, a plurality of panels pivotally supported by said shaft and including one 20 or more locking panels, and means for automatically swinging said locking panels when said shaft is rotated to or from a predetermined position.

23. In a display cabinet of the character described, the combination with a case or cabinet, of a rotatable shaft mounted to reciprocate to and from a position within the case or cabinet, a plurality of panels arranged in parallel relation and pivotally supported by said shaft, means for preventing 30 pivotal movement of all of said panels while said shaft is in a rearward position, and for imparting pivotal movement to a portion of said panels when the shaft has been partially rotated in its forward position.

24. In a display cabinet of the character described, the combination with a case or cabinet, of a rotatable shaft mounted to reciprocate to and from a position within said case or cabinet, a plurality of panels arranged in parallel relation and pivotally supported by said shaft, a non-rotatable cam concentric with and independent of said shaft, and panel controlling members coöperating with said cam to prevent pivotal movement of all of said panels while said shaft is in rearward position, and for imparting pivotal movement 50 to a portion of said panels when the shaft has been partially rotated in its forward position.

25. A rotatable display rack of the character described, comprising a plurality of 55 members mounted for pivotal movement and including one or more locking members, and means for automatically imparting pivotal movement to said locking members when said rack is rotated in either direction from a predetermined position.

26. A rotatable display rack of the character described, comprising a plurality of members mounted for pivotal movement, means carried by said rack and movable

relatively thereto for imparting pivotal 65 movement to one or more of said members, and means coöperating with said movable means and stationary with respect thereto for controlling the actuation thereof.

27. A display rack of the character described comprising a rotatable shaft, means for supporting the same, a plurality of parallel panels supported by the shaft, said panels being arranged in oppositely disposed sets, and means for simultaneously 75 preventing pivotal movement of all of said panels and for releasing all of the panels of either set when the shaft is in predetermined positions in its rotative movement.

28. A display rack of the character de- 80 scribed comprising a rotatable shaft, means for supporting the same, a plurality of panels pivotally supported by said shaft, means carried by the shaft and movable relatively thereto for imparting pivotal movement to 85 the end panels, and means coöperating with said movable means and stationary with respect thereto for controlling the actuation thereof.

29. A display rack of the character de- 90 scribed comprising a rotatable shaft, means for supporting the same, a plurality of panels pivotally supported by said shaft, movable means carried by the shaft for imparting pivotal movement to the end panels, and 95 a cam concentric with said shaft and stationary with respect thereto and controlling the actuation of said panel moving means.

30. A display rack of the character de- 100 scribed comprising a rotatable shaft, means for supporting the same, a plurality of panels pivotally supported by said shaft, slides connected with the end panels, a cam concentric with and independent of said shaft, and means for yieldingly holding said 105 slides in engagement with said cam.

31. A display rack of the character de- 110 scribed comprising a rotatable shaft, means for supporting the same, a plurality of panels pivotally supported by said shaft, a non-rotatable cam concentric with said shaft and provided with a slot leading in from the periphery thereof, and means yieldingly engaging said cam and adapted to enter said slot to impart pivotal movement to the end 115 panels.

32. A display rack of the character de- 120 scribed comprising a rotatable shaft, means for supporting the same, and a plurality of panels arranged in parallel relation and pivotally supported by said shaft, means for locking said panels against pivotal movement, said locking means including means operated by rotation of said shaft in either direction from a predetermined position to 125 initiate pivotal movement of the end panels.

33. A display rack of the character de- scribed comprising a rotatable shaft, means

for supporting the same, a plurality of panels pivotally supported by said shaft and including one or more locking panels, and means for automatically swinging said locking panels when said shaft is rotated in either direction from a predetermined position.

In testimony whereof I have hereunto set my hand in presence of two subscribing witnesses.

WILLIAM T. HORMES.
